(57) **CLAIM**

I claim the ornamental design for a remote grease fitting, as shown and described.

DESCRIPTION

FIG. 1 is a perspective view of a remote grease fitting, showing my new design;

FIG. 2 is a right side elevational view thereof;

FIG. 3 is a left side elevational view thereof;

FIG. 4 is a front elevational view with the rear elevational view being a mirror image thereof;

FIG. 5 is a top plan view thereof; and,

FIG. 6 is a bottom plan view thereof.
